UNITED STATES PATENT OFFICE.

FREDERICK E. HILL, OF HASTINGS, MICHIGAN.

DESIGN FOR A KNITTING-STAND.

52,530.

Specification for Design.

Patented Oct. 8, 1918.

Application filed April 15, 1918. Serial No. 228,791. Term of patent 3½ years.

To all whom it may concern:

Be it known that I, FREDERICK E. HILL, a citizen of the United States, residing at Hastings, in the county of Barry and State of Michigan, have invented a new, original, and ornamental Design for Knitting-Stands, of which the following is a specification, reference being had to the accompanying drawing, forming a part thereof.

The figure is a perspective view of a knitting stand showing my new design.

I claim:

The ornamental design for a knitting stand, substantially as shown.

In testimony whereof I hereunto affix my signature.

FREDERICK E. HILL.
